Machine & Foundry Company, a corporation of New
Jersey

Filed Dec. 14, 1961, Ser. No. 159,225
14 Claims. (Cl. 273—43)

This invention relates to bowling pin respotting mechanisms of bowling pin spotting machines for automatically spotting and respotting bowling pins on the playing bed of a bowling alley.

The present invention is an improvement over bowling pin spotting machines of a type similar to that disclosed in U.S. Patent 2,781,195—Holloway et al. In such prior art machines, the respotting units are supported on a spotting-respotting table which is raised and lowered relative to the pin deck of a bowling alley for respotting standing pins on the pin deck. Normally, such machines are operated so that after the first ball of a frame has been thrown and there remains at least one standing pin on the pin deck, the table is lowered and each respotting unit, which is provided with a pair of grippers that grip the head of a standing pin, picks up such pin upon subsequent upward movement of the table. Then, a pin sweep clears the alley of deadwood and the table is lowered so that the respotting units respot the standing pins on the pin deck. After the last ball of a frame has been thrown, the table is not lowered and the pin sweep sweeps the deadwood and standing pins, if any, from the alley into the pit.

Some of these prior art machines are also equipped with annunciators that are actuated by the respotting units to indicate which pins are standing after the first ball of a frame has been thrown. But, since after the last ball of a frame has been thrown, the table is not lowered, such annunciators are not actuated. Therefore, the player must rely solely on his ability to be able to correctly identify the number of pins which are standing.

Furthermore, it occasionally happens during the course of play that a flying pin will strike the prior art respotting units and cause the grippers to be moved toward each other and locked so that when the table is subsequently lowered, the locked grippers can engage the top of a standing pin and either damage the pin or the spotting machine. Where annunciators are also used, the locked grippers improperly indicate the presence of a standing pin.

Accordingly, one of the objects of this invention is to provide an improved respotting mechanism for an automatic bowling pin spotting machine.

Another object is to provide a bowling pin spotting machine with improved means for indicating which pins are standing after each ball of a frame has been thrown.

Still another object is to provide an improved respotting mechanism which cannot be locked in a closed position by a flying pin.

A further object is to provide an improved respotting mechanism, which includes a plurality of respotting units and a control system therefor, that is not subject to being actuated by a flying pin and which will indicate the presence and positions of those pins which are standing after each ball of a frame has been thrown.

In order that the manner in which these and other objects are attained in accordance with the invention can be understood in detail, reference is had to the accompanying drawings, which form a part of this specification, and wherein:

FIGURE 1 is a schematic diagram for a bowling pin spotting machine embodying the invention;

FIGURE 2 is a side elevational view, partly in section, and with portions broken away, of a respotting unit

2

illustrating the unit prior to actuation thereof by a standing pin; and

FIGURE 3 is a view similar to FIGURE 2 illustrating the respotting unit when a bowling pin is gripped thereby.

5 Referring now to the drawings, the embodiment there illustrated includes a table T and a plurality of respotting units 1-10 which, except for the latching mechanism, are similar to those in U.S. Patent 2,781,195—Holloway et al., to which reference can be had for a more detailed description.

10 Respotting units 1-10 are arranged on table T in a triangular relationship with each unit above the position of a different one of the bowling pins spotted on the pin deck of a lane or alley. Respotting unit 1 is above the head of #1 pin, respotting unit 2 is above the #2 pin, etc. The respotting units are similar, so that only one need be described in detail.

15 With reference to FIGURES 2 and 3, respotting unit 1 is mounted on table T by a bracket 12 keyed to a shaft 13, the respotting unit comprising a clamping member 14, a pair of grippers 15 and 16, and latch means 17. Clamping member 14 comprises a horizontal clamping pad 18 preferably formed of resilient material such as sponge rubber, and a rigid support member having a lower horizontal plate 19 backing up clamping pad 18 and a vertical portion 20 extending upwardly from plate 19. A pair of parallel links 21 and 22 are pivotally connected to portion 20 and to a dependent portion 23 of bracket 12 and pivotally mount the clamping member on the table.

20 30 Grippers 15 and 16 comprise a pair of opposed gripping jaws 24 and 25 of a suitable resilient material such as sponge rubber, supported on a pair of gripping jaw support members 26 and 27. These support members, in turn, are supported by a plurality of rollers 28 guided by a horizontal track 29 secured to clamping member 14 so that the gripping jaws can move horizontally toward and away from each other in a plane parallel to the pin deck and transversely of a standing pin P.

35 40 Grippers 15 and 16 move in response to relative movement between table T and clamping member 14 by means of rollers 30 and 31 received in cam tracks 32 and 33 of a frame member 34 supported on a horizontal track 35 by a pair of rollers 36. Rollers 30 and 31 are secured to grippers 15 and 16, respectively, and track 35 is secured to bracket 12 so that as table T moves relative to clamping member 14, frame member 34 moves relative to the rollers 30 and 31 and thereby causes rollers 30 and 31 to travel along portions of cam tracks 32 and 33. Cam tracks 32 and 33 include lower divergent portions and upper parallel vertical portions, the lower portions being operative upon downward movement of table T relative to the clamping member to move grippers 15 and 16 toward each other and thereby grip the standing pin causing such movement.

45 50 Upward movement of table T relative to clamping member 14 causes lower portions of cam track 32 and 33 to move grippers 15 and 16 away from each other to release the pin gripped thereby. When table T is above that position at which any of the respotting units can engage a standing pin, clamping member 14 is gravity biased, due to its own weight and to the weight of the parts connected to it, to the position shown in FIGURE 2 wherein rollers 30 and 31 engage the lower end of cam tracks 32 and 33.

55 60 65 In accordance with the illustrated embodiment, it is contemplated that the movement of the table T be controlled by a system similar to that disclosed in U.S. Patent 2,974,955. For a normal two-ball frame type of game, such movement is as follows. After the first ball of a frame has been thrown, table T is moved through a respotting cycle which comprises lowering and raising the table to enable standing pins to be picked up and, after the alley has been cleared of deadwood, lowering and

raising the table to respot the pins on the pin deck. After the second ball has been thrown, table T is moved sequentially through a detecting cycle and through a spotting cycle. During the detecting cycle, table T is lowered and raised to detect standing pins. Then, after the alley has been cleared of such pins and any deadwood, the table is lowered and raised through a spotting cycle to spot a complete set of pins on the pin deck.

Latch means 17 comprises a latch member 37 rigidly mounted on portion 20 of clamping member 14 for movement therewith, and a latch hook 38 pivotally mounted on bracket 12 for vertical movement therewith and for pivotal movement relative thereto. This pivotal movement is caused by a solenoid 39 and a restoring spring 40 upon energization and de-energization of the solenoid. Solenoid 39 is supported in a vertical position on bracket 12 and has a vertically movable plunger 41. Latch hook 38 is in the form of a bell crank lever and has its upper end connected to plunger 41 so that vertical movement of plunger 41 causes the lower or free end of latch hook 38 to move through a small arc.

Latch hook 38 is movable alternately between an inoperative position (FIGURE 2), and an operative position (FIGURE 3). When solenoid 39 is energized, the latch hook is moved to its operative position. When solenoid 39 is de-energized, the latch hook is movable to its inoperative position.

Near the beginning of the respotting cycle, solenoid 39 is energized and latch hook 38 is moved to its operative position wherein the free end thereof can travel along a vertical path intersecting the free end of latch member 37. If there is a standing pin beneath clamping member 14, the lowering of table T causes latch hook 38 to cam over latch member 37 whereby subsequent upward movement of table T moves latch hook 38 into locking engagement with latch member 37, as illustrated in FIGURE 3.

After the grippers are locked, solenoid 39 is de-energized but, because the free ends are hooked, latch hook 38 and latch member 37 remain locked. When the table is lowered to respot pin P on the alley, the base of the pin engages the pin deck and causes latch hook 38 to move downwardly a small distance relative to latch member 37. Such movement disengages latch hook 38 and allows spring 40 to move the latch hook to its inoperative position as shown in FIGURE 2, whereby subsequent upward movement of table T disengages grippers 15 and 16 and resspots pin P on the pin deck.

The locking and unlocking of latch hook 38 and latch member 37 might be better understood in view of the following. With reference to FIGURE 3, line 69 represents the position of clamping member 14, using the upper edge of track 29 as a reference, when clamping member 14 clamps pin P against the pin deck. Line 71 represents the lowest position of table T during the respotting cycle and line 70 represents the position of table T when the latch means 17 is locked, lines 70 and 71 using the lower edge of track 35 as a reference.

During the respotting cycle, table T is lowered into and raised from position 71 to allow any standing pins to be picked up. A standing pin P arrests downward movement of clamping member 14 at 69 and allows latch hook 78 to cam over latch member 37 whereby subsequent upward movement of table T from position 71 to position 70 moves latch hook 38 into locking engagement with latch member 37. During movement of table T between positions 70 and 71, pin P remains in engagement with the pin deck. Consequently, when table T is lowered to respot pin P on the pin deck and moves downwardly from position 70 to position 71, latch hook 38 moves downwardly and, because solenoid 39 is then de-energized, disengages latch member 37 in the manner previously described.

Mounted above cross bar 42 of portion 23 is a single-pole, single-throw, normally-closed switch 43 having an exposed button that is actuated by a lever 44 connected

to one end of a spring 45. This spring has its other end connected to link 21 and is operative to prevent damage to switch 43 caused by over-travel of lever 44. When respotting unit 1 does not engage a standing pin, lever 44 actuates and opens switch 43, as illustrated in FIGURE 2. However, when a standing pin causes clamping member 14 to move upwardly relative to table T, lever 44 is pivoted away from switch 43 and thereby closes the switch.

Referring now to FIG. 1, the illustrated embodiment also includes an annuciator A provided with a plurality of lamps L1-L10 arranged in a triangular relationship corresponding to the positions of pins spotted upon the pin deck of an alley, the annuciator being exposed for view by a player so that illumination of the lamps indicates which pins are standing. That is, when lamp L1 is illuminated, it indicates that the #1 pin is standing, when lamp L2 is illuminated, it indicates that the #2 pin is standing, etc.

With reference to respotting unit 1, each respotting unit is associated with a double-pole, single-throw, normally open electromagnetic relay comprising a coil 47, a first set of contacts 48 and a second set of contacts 49. Power for operation of the electrical components of the illustrated embodiment is derived from a pair of power lines 50 and 51 adapted to be connected to a suitable source of power (not shown). Switch 43 is connected in series with coil 47 across lines 50 and 51. Contacts 49 are connected across the power lines 50 and 51 in series with lamp L1 so that operation of contacts 49 controls the operation of lamp L1.

The illustrated embodiment also includes a master control system comprising a pair of switches 52 and 53 actuated by rotary cams 54 and 55 driven by a timing motor 56, and a pair of switches 57 and 58 actuated by rotary cams 59 and 60 driven by a timing motor 61. Switch 57 is connected in series with motor 56 for controlling the operation thereof, whereas the operation of motor 61 is controlled by a double-pole, single-throw, normally open relay having a coil 62 and a pair of sets of contacts 63 and 64, motor 61 being in series with contacts 63.

The timing motors are arranged so that, after each ball of a normal two-ball frame has been thrown, motor 61 rotates cams 59 and 60 through one revolution (360°) and motor 56 rotates cams 54 and 55 through one-half revolution (180°).

A ball actuated pit switch 65 is connected in parallel with a manual "strike" switch 66 and with a series circuit comprising switch 58 connected in series with contact 64, the resultant circuit being connected in series with coil 62 across lines 50 and 51.

Switch 52 is connected in series with contacts 48 of each respotting unit so that, within each unit, the series circuit of switch 52 and contacts 48 is in parallel with switch 43 of that particular unit. Switch 53 is connected in series with each solenoid 39 of respotting units 1-10 so that switch 53 controls operation of all of the solenoids and of the latch hooks.

The master control system operates in a timed relationship with the control system for table T so that the illustrated embodiment operates in the following manner. The first ball of a frame momentarily closes pit switch 65 and thereby allows current to flow through coil 62 to close contacts 63 and 64. The closing of contacts 63 energizes motor 61 and thereby rotates cams 59 and 60. Cam 60 is arranged so that, upon initial rotation thereof, switch 58 closes and establishes a hold circuit for energizing coil 62. At the end of one revolution, cam 60 opens switch 58 and thereby de-energizes coil 62, causing contacts 63 and 64 to open. As cam 59 rotates, it closes switch 57 at the beginning of each revolution and opens switch 57 at the end of each revolution, and thereby operates motor 56 only so long as switch 57 remains closed, that is, for the period during which motor 61 rotates cam 59 through one revolution.

As motor 56 rotates cams 54 and 55 from their start positions illustrated in FIG. 1, switches 52 and 53 are closed. The closing of switch 53 actuates all of solenoids 39 and thereby pivots all of latch hooks 38 from their inoperative positions to their operative positions. This is done before any of the respotting units initially engages any standing pin. Switch 53 is opened and solenoid 39 is de-energized after the latch hooks 38 lock with latch members 37, whereby standing pins are picked up and resotted in the manner previously described.

Cam 55 is arranged so that switch 53 is open at all times other than above. Consequently, during other portions of the cycles and during the course of play, the latch members 37 cannot be engaged by and locked with the latch hooks 38.

Actuation of motor 56 rotates cam 54, which closes switch 52 throughout a portion of each half revolution or cam 54. When switch 52 is closed, a potential is applied across contacts 48 so that, if a standing pin is beneath the resspotting unit associated with such contacts, the closing of switch 43 in response to the presence of such pin will energize coil 47 and thereby close contacts 48 and 49 to establish, through contacts 48, a hold circuit for coil 47. Cam 54 is arranged to close switch 52 so that this hold circuit maintains the lamp associated with it illuminated for a sufficient period of time to enable a player to visually observe via annunciator A which pins are standing.

The second ball of a frame closes switch 65 and thereby energizes coil 62 and closes contacts 63 and 64 so that motor 61 rotates through a second complete revolution. During rotation of motor 61 through the second revolution of each frame, motor 56 rotates cams 54 and 55 through the second half of one revolution, during which time switch 53 is open and switch 52 is closed, to detect and indicate which, if any, pins are standing, in a manner similar to that described with reference to the first ball. Since switch 53 remains open, solenoid 39 remains de-energized. Therefore, resspotting units 1 are inoperative and any standing pins are swept into the pit of the alley by sweep means (not shown).

In the event a strike is made by the first ball, switch 66 is actuated manually to produce an artificial second ball cycle whereby motor 56 rotates cams 54 and 55 through 180° to their normal start positions to condition the system for the next frame.

If, during the course of play, a flying pin accidentally strikes one of clamping members 14, the grippers 15 and 16 cannot be locked because, during the course of play, the solenoids 39 are not energized. The only effect of such a pin would be to cause the momentary closing of switch 43 which momentarily actuates the relay and thereby momentarily lights the lamp associated with the resspotting units struck by the flying pin. If a suitable time delay is built into the relay, then such flying pin will not even cause a momentary illumination of any of the lamps.

Whereas only a single embodiment has been illustrated, it will be apparent to those skilled in the art that many changes can be made both in the details of construction and arrangement of parts without departing from the scope of the invention as defined in the appended claims.

What is claimed is:

1. In a bowling pin spotting machine, the combination of a plurality of resspotting units for resspotting bowling pins during a resspotting cycle of the bowling pin spotting machine, each of said units comprising a pair of grippers automatically self-operable to grip a standing pin, latch means alternately operative and inoperative for locking said grippers in engagement with a standing pin to enable said grippers to pick up and to respot such pin, and means including an electromagnet for operating said latch means; switch means operably connected for

simultaneously actuating all of said electromagnets; and timing means operative to actuate said switch means and thereby operate said latch means only during said resspotting cycle.

5 2. In a bowling pin spotting machine, the combination of a plurality of resspotting units movable through a plurality of cycles including a resspotting cycle and a detecting cycle; indicating means operative to indicate which pins are standing; each of said resspotting units comprising a pair of grippers adapted to grip a standing pin automatically during said resspotting cycle and said detecting cycle, latch means alternately operative and inoperative for locking said grippers in engagement with a standing pin gripped thereby, first means for actuating 10 said latch means, and second means operably connected for automatically actuating said indicating means in response to the presence of a standing pin during both said resspotting cycle and said detecting cycle; and means for controlling operation of said first means to effect 15 operation of said latch means only during said resspotting cycle.

3. In a bowling pin spotting machine, the combination of a table; a plurality of resspotting units carried by said table, each of said units comprising clamping means 25 adapted to engage the head of a standing pin and clamp such pin against the pin deck whereby such pin arrests downward movement of said clamping means, said clamping means being mounted so that when its downward movement is arrested, relative movement occurs 30 between it and said table, a pair of grippers adapted to move into and away from gripping engagement with a standing pin in response to relative movement between said clamping means and said table, latch means for locking said grippers in engagement with a standing pin and automatically unlocking said grippers when such pin is 35 resotted, said latch means including a latch member and a detent, said detent being movable between operative and inoperative positions for engagement with said latch member, and means including an electromagnet for moving said detent between said positions; switch means operably connected for simultaneously actuating all of said electromagnets; and timing means operably connected for controlling operation of said switch means so that 40 said grippers can be locked during predetermined portions of the operation of the bowling pin spotting machine.

4. In a bowling pin spotting machine, the combination of a resspotting table; indicating means including a plurality of lamps operative to indicate which pins are standing; 50 a plurality of resspotting units carried by said table for movement through a plurality of cycles including a resspotting cycle for resspotting standing pins and a detecting cycle merely for detecting the presence of standing pins, each of said units comprising clamping means 55 adapted to engage the head of a standing pin, means mounting said clamping means for movement relative to said table upon engagement of said clamping means with a standing pin, a pair of grippers operatively connected for gripping a standing pin in response to said relative movement between said clamping means and said table, latch means alternately operative and inoperative for locking said gripping means in engagement with a standing pin, means including an electromagnet operably connected for operating said latch means in response to actuation of said electromagnet, and first switch means 60 operably connected for actuating one of said lamps in response to said relative movement between said clamping means and said table; second switch means operably connected for simultaneously actuating all of said electromagnets; and timing means operably connected for actuating said second switch means so that said latch means is operative during said resspotting cycle and is inoperative at times including said detecting cycle other than during said resspotting cycle.

5. A bowling pin spotting machine in accordance with claim 4 wherein said second switch means comprises a single-pole, single-throw switch.

6. A bowling pin spotting machine in accordance with claim 5 wherein said timing means includes a rotary cam operably connected for actuating said switch, and a timing motor for driving said cam.

7. A bowling pin spotting machine in accordance with claim 6 wherein each of said first switch means comprises an electromagnetic relay having a set of contacts connected in series with the one of said lamps associated therewith, and a single-pole switch operably connected to actuate said relay in response to said relative movement between said clamping means and said table; said bowling pin spotting machine further including a single switch operably connected to all of said relays, and a rotary cam for actuating said single switch, said rotary cam being driven by said timing motor and operative to establish a hold circuit for each of said relays during at least said detecting cycle.

8. In a bowling pinspotting machine, the combination of a plurality of respotting units for respotting standing pins during a respotting cycle; each of said units comprising gripping means responsive to engagement with a bowling pin to be automatically self-closing about the pin, latch means adapted to be placed in operation to lock said gripping means in closed position about said standing pin, and means operably connected to said latch means for placing the same in operation; and means for simultaneously actuating all of said latch-operating means only during said respotting cycle.

9. A bowling pinspotting machine in accordance with claim 8 wherein said last-recited means comprises timing motor means, and a bowling ball-operated pit switch for initiating operation of said timing motor means at the start of the respotting cycle.

10. In a bowling pinspotting machine, the combination of a plurality of respotting units each comprising gripping means adapted to grip a standing pin automatically upon engagement therewith, latch means alternately operative and inoperative for locking said gripping means in engagement with a standing pin, and an individual electromagnetic means for controlling the operation of said latch means; and a common control means including switch means therein for simultaneously operating all of said electromagnetic means to effect operation of said latch means during a limited period of time.

11. A bowling pinspotting machine in accordance with claim 10, including cam means for operating said switch means, and timing motor means for operating said cam means.

12. In a bowling pinspotting machine, the combination of a plurality of respotting units, means lowering and raising said plurality of respotting units successively immediately following the first ball in a frame to detect, lift and respot standing pins and again immediately following a second ball to detect and signal the presence of the remaining standing pins, each of said units comprising:

(a) gripping means adapted to be closed automatically upon movement of the unit downwardly into engagement with a standing pin and thereafter to hold the pin upon upward movement,

(b) means in association with said gripping means for detecting and signalling the presence of a pin engaged thereby,

(c) latch means directly operable on said gripping means and movable to an operative position in which the gripping means is held in a closed position upon its engagement with a standing pin, and

(d) individual means controllable to place said latch means either in said operative position or in an inoperative position in which the gripping and lifting of a standing pin is prevented, and control means for the plurality of said individual means that are controllable to place said latch means in

operative and inoperative positions, said control means effecting thereby the placement of each said latch means in said operative position only immediately following said first ball and in inoperative position during the actual rolling of the first and second balls against standing pins.

13. In a bowling pinspotting machine, the combination of a plurality of respotting units, means for lowering said plurality of respotting units to a predetermined lower level and raising the same to an inactive upper position successively immediately following both the first and second balls in a frame, each of said respotting units comprising:

(a) a jaw-type gripping means adapted to close about a standing pin and thereafter to hold the pin upon upward movement,

(b) a member normally operable by engagement with a pin upon movement of the respotting units fully to said lower level to move said jaw-type gripping means to a closed position,

(c) means associated with said gripping means for detecting and signalling the presence of a pin therein,

(d) latch means directly operable on said gripping means and movable to an operative position in which the gripping means is held in said closed position when moved thereto by the operation of said member, and

(e) individual means controllable to place said latch means either in said operative position or in an inoperative position in which the gripping means is not held closed during upward movement thereof, and common control means for the plurality of said individual means that are controllable to place said latch means in operative and inoperative positions, said control means effecting thereby the placement of each said latch means in said operative position only during lowering and raising thereof immediately following rolling of said first ball and in inoperative position during the actual rolling of the first and second balls against standing pins.

14. In a bowling pinspotting machine, the combination of a plurality of respotting units, means for lowering and raising said plurality of respotting units successively immediately following the first ball in a frame to detect, lift and respot standing pins and again immediately following a second ball to detect the remaining standing pins, each of said units comprising:

(a) jaw-type gripping means responsive to engagement with a bowling pin to be automatically self-closing about the pin and thereafter to hold the pin in a raised position,

(b) means associated with said gripping means for detecting the presence of a pin therein,

(c) a latch member engageable with a portion of said gripping means and movable to an operative position in which the gripping means is held in closed position after being closed by the action of a pin, and

(d) a solenoid operably associated with said latch member to control movement thereof between said operative position and an inoperative position in which the gripping means will not be held closed if engaged by a pin,

and a common electrical control system for operating the solenoids associated with the plurality of said latch members, said system effecting thereby the movement of said latch members to operative position only immediately following the rolling of said first ball and to an inoperative position during the actual rolling of the first and second balls against standing pins.
